UNITED STATES PATENT OFFICE.

ABEL FERNÁNDEZ, OF MEXICO, MEXICO.

AUTOMATIC CUT-OUT.

1,372,495.

Specification of Letters Patent. Patented Mar. 22, 1921.

Application filed January 2, 1918. Serial No. 210,050.

To all whom it may concern:

Be it known that I, ABEL FERNÁNDEZ, a citizen of Mexico, residing at Avenida Pino Suarez 21, Mexico city, Mexico, have invented certain new and useful Improvements in Automatic Cut-Outs, of which the following is a specification.

This invention relates to improvements in automatic circuit breaking devices, particularly to those devices commonly known in the art as thermal cut-outs which when interposed in electrical circuits will serve as means to prevent the occurrence of excessive or abnormal currents therein.

15 The invention has for its dominant object to provide an automatic circuit breaker which when interposed in the conductors of an electrical circuit will afford an effectual means therefor to prevent the overloading 20 of the same or the short circuiting thereof, thus, eliminating the danger of overheating and the possibilities of fire resulting therefrom.

It is also an object of the invention to 25 provide an automatic circuit breaker of the character mentioned, which may have the tension of the thermal regulating element thereof adjusted to permit the release of the circuit closing means when the strength of 30 the current exceeds a predetermined value, thus allowing loads differing in strength to be conveyed by the conductors of a circuit in which the same is interposed.

Other objects relate to considerations of 35 economy of production, durability in use, and convenience in operation of the several mechanisms or parts entering into the construction of elements and the above defined general organization of said elements.

40 Other improvements and novelties in the details of construction and arrangement of the various parts of the device will be brought out more in detail in the description to follow, which, for a clear understanding 45 of the invention, should be considered in connection with the accompanying drawings forming part hereof, and wherein is disclosed for the purpose of illustration, a convenient and satisfactory embodiment of the 50 present invention.

In the drawings:

Figure 1 is a top plan of the improved cut-out,

Fig. 2 is a vertical longitudinal section 55 therethrough, taken on the line 2—2 of Fig. 1.

Fig. 3 is a vertical transverse section through the same taken on the line 3—3 of Fig. 1,

Fig. 4 is a fragmental detail in perspective 60 of one contact, and,

Fig. 5 is a detail in section through the means for securing one end of the thermal element.

Similar reference characters refer to similar parts throughout the several views of the drawings.

Having more particular reference to the drawings, 1 represents the base of the improved cut-out device, the same being provided with a hinged cover 2 having suitable locking means 3 arranged thereon and engageable with said base 1 for an obvious purpose.

Bracket arms 4 are secured to the upper 75 face of the base 1 which may be and preferably is formed of insulating material such as fiber, porcelain or the like. One of the brackets has one end of a metal piece 5 secured thereto while the remaining end is 80 arranged adjacent the other bracket, which affords a stop therefor; said piece being provided with a contact 6 adjacent one end thereof and having the free end of an electrical conductor 7 secured thereto.

Another bracket 8 is secured to the upper 85 face of the base 1 as at 9 and has one end of a spring arm 10 secured thereto, the free end of said arm extending to a point in proximity to the contact 6 and carrying a 90 contact element 11 thereon, said contact element being insulated from the spring arm by means of a fiber sleeve 12 arranged thereabout. To this contact element 11 a branch conductor 13 is connected.

Secured to the base 1 at a point in proximity to the free end of the spring arm 11 is a bracket 14 provided with an upwardly bent apertured guide lug 15 and a second upwardly bent lug 16 to which one end of 100 a spring arm 17 is secured. The arm 17 is so arranged as to have its free end arranged at a point adjacent the contact member 6 and as a consequence, when the same is engaged with the free end of the arm 105 10, the contact element 11 carried thereby will be positively maintained in engagement with the contact 6, thus, completing the circuit through the several conductors 7 and 13. A hooked finger 18 is carried upon the 110 free portion of the spring arm 17 and is adapted to be engaged with one end of the

thermal regulating element, hereinafter described.

As means for moving the contact element 11 carried by the arm 10 into engagement 5 with the contact 6 an operating piece 19 is slidably received through the apertured lug 15 and has one end thereof reduced as at 20 and adapted to be engaged with the free end of the arm 10, while the remaining end of 10 said piece is provided with a button or head 21 preferably formed of an insulating material for an obvious purpose. This operating piece 19 is normally held in retracted position by means of a spring arm 22 se- 15 cured to a bracket 23 mounted on the insulat- ing base 1 and having its free end notched and engaged over said operating piece. A contact piece 19' is carried by the operating piece 19 and is normally engaged with the 20 lug 15, thus, permitting the passage of current to the thermal element, hereinafter described. An electrical conductor 24 forming the remaining side of the circuit in which the cut-out is interposed is connected 25 to the spring arm 22 and due to the engage- ment of said arm with the bracket 14 when in retracted position, current will be per- mitted to flow therethrough into the spring arm 17.

30 The thermal regulating element of the cut- out comprises a length of expansible wire designated by the numeral 25, one end of which is secured to the hooked finger 18 while the remaining end is engaged with a bracket 26 adjustably connected to an ad- justing screw 27 mounted on the bracket 28 which in turn is secured to the base 1 at a point opposite to the arrangement of the spring arm 17. Obviously, by adjusting 35 the screw 27 the thermal element 25 may be placed under varying tensions and as a consequence will cause disengagement of the 40 arm 17 from the arm 10 at varying times.

In operation, the automatic cut-out is 45 interposed in an electrical circuit by having conductors 7 and 24 connected to the contact 6 and the bracket 23. The branch conductor 13 is of course connected to the bracket 28 and to the contact 11 carried on the arm 10. 50 The operating piece 19 is now pushed in- wardly causing the contact 11 to be engaged with the contact 6, thus, closing the circuit. With the arm 10 in position to permit eng- 55 gagement of the contact 11 with the contact 6, it will be noted that the free end of the arm 17 is engaged behind the free end of the same and as a consequence, undue disen- gagement thereof will be prevented under normal conditions. Obviously, current will 60 flow through the conductor 24 into the arm 17 and from there through the thermal ele- 65 ment 25 from whence it will be introduced into the conductor 7. However, should the circuit be subjected to excessive or abnormal

25 to the travel of the current therethrough will be such as to heat the same, thus, caus- ing expansion and permitting the spring arm 17 to be disengaged from the free end of the arm 10. Upon such disengagement, 70 the arm 10 will immediately spring to its normal position, interrupting the flow of current through the contacts 6 and 11. In this way, the line will be cut out and all- dangers attributable to the overloading of 75 the same either by excessive current flows or other abnormal conditions will be positively prevented. When the element 25 has cooled and contracted, the operating piece may be again moved inwardly to cause engagement 80 of the contact 11 with the contact 6, said contacts being of course maintained in en- gagement by the spring arm 17 which en- gages with the free end of the arm 10. Therefore, it will be noted that my improved 85 cut-out does not require the refitting of the same with thermal regulating devices after each operation thereof caused by the pres- ence of abnormal currents.

Manifestly, the construction shown is 90 capable of considerable modification and such modification as is within the scope of my claims, I consider within the spirit of my invention.

I claim:—

1. In a circuit breaker, a base, spring arms on said base, a stop engageable with the free end of one of the arms for limiting movement thereof in one direction, the other spring arm normally tending to move away 100 from the first mentioned arm, interengage- able contacts carried on the terminals of the arms, a bracket carried by the base, spring latch means carried by the bracket engageable with the second mentioned arm 105 for normally effecting engagement between the contacts, means insulating the contact member of the second mentioned arm from said arm, a thermo-sensitive element con- nected with the latch means operable upon 110 expansion, to permit displacement of the latch member and release of the second men- tioned arm, said bracket, latch means and thermosensitive element being constructed of 115 conducting material, and an electrical con- nection between the thermo-sensitive element and the insulated contact.

2. In a circuit breaker, a base, spring arms on said base, a stop engageable with the end of one of the arms for limiting the move- 120 ment thereof in one direction, the other spring arm normally tending to move away from the first spring arm, interengageable contacts carried by the free ends of the arms, a bracket carried by the base, a spring latch 125 member carried by the bracket engageable with the terminal of the second mentioned spring arm to maintain the contact thereof in engagement with the contact of the first mentioned spring arm, the inherent resil- 130

iciency of the spring latch member normally tending to move the latter to arm releasing position, a plunger slidably mounted in the bracket engageable with the second mentioned spring arm to move the latter into operative position with relation to the first-mentioned spring arm, a thermo-sensitive element connected with one terminal of the spring latch member and adapted, upon expansion, to permit the latter to move from engagement with the terminal of the second

mentioned spring arm, and an adjustable connection between the opposite terminal of the thermo-sensitive element and the base for varying the normal position of the 15 spring latch member with relation to the adjacent terminal of the second mentioned spring arm.

In testimony whereof, I affix my signature hereto.

ABEL FERNÁNDEZ.
